UNITED STATES PATENT OFFICE.

FREDERICK E. GOLDSMITH, OF MIDDLETOWN, OHIO, ASSIGNOR TO THE CERAMIC MACHINERY COMPANY, OF HAMILTON, OHIO.

MACHINE FOR COATING.

1,027,414.

Specification of Letters Patent. Patented May 28, 1912.

Application filed July 26, 1906. Serial No. 327,925.

To all whom it may concern:

Be it known that I, FREDERICK E. GOLDSMITH, a citizen of the United States, and a resident of Middletown, in the county of Butler and State of Ohio, have invented a new and useful Machine for Coating, of which the following is a specification.

My invention relates to machines for supplying coating to objects such, for example, as tile.

An important object is to provide a simple and economically built machine for cheaply and efficiently performing the work designated.

The characteristics and advantages of the invention are hereafter pointed out in detail in connection with the accompanying drawing, which shows in diagrammatic form an exemplifying structure in which the said invention is embodied.

The figure is a diagrammatic view partly in elevation and partly in section.

1 designates a frame; 2, standards, 3, a feed apron or belt carried on a pulley 4 mounted in standards 2 and another pulley not shown; 5, a carry-off belt running on pulley 6 carrying a portion of the belt which is adjacent to the coating roll; 7, a coating roll mounted revolvably in standards 2; 8, a pressure roller mounted above the coating roll; 9, an adjusting shaft; 10, eccentrics thereon rotatable on the center 11; 12, links connecting the eccentrics with the axis of roller 8; 13, a gear rotatably secured to the frame and meshing with a gear on the shaft of the coating roll; 14, an idle pinion intermediate gear 13 and a gear on the shaft of the pressure roller 8; 15, 16, links connecting pinion 14 radially with the axes of gear 13 and shaft of the pressure roller 8, so as to keep said pinion in mesh with the gears irrespective of the position of the pressure roller.

The coating roll is rotated from any suitable source of power, or power may be applied to gear 13 or shaft of the pressure roller. Rotation of the shaft of coating roll 7, for example, transmits motion to gear 13 thence through idle pinion 14 to shaft of pressure roller 8. The adjacent surfaces of the coating roll and pressure roller therefore rotate in the same direction, as indicated by the arrow. The feed belt and the carry-off belt are simultaneously driven by

any suitable means, as shown by arrow, and objects such as biscuit (unglazed tile) are placed on the feed belt and are carried through and to the pressure roller and coating roll and away on the carry-off belt.

20 is a trough below the coating roll; 21, a tub forming a main receptacle for coating material; 22, a shaft conveniently journaled in sides of the tub; 23, a frame carried by the shaft; 24, an arm on the shaft conveniently exterior to the tub, and having a pin; 25, a link or pitman moved forward and back by any suitable means and connected to the pin, serving to oscillate the frame 23; 26, a scraper or agitator blade fixed to the frame and adjacent to or in contact with the inner surface of the tub; 27, a scoop carried by frame 23; 28, a plate conveniently secured to the tub, and either fixed, or movable, or adjustable on a pivotal mounting such as 29.

In operation, movement of the pitman 25 causes the frame 23 to oscillate in the tub. The agitator blade 26 moves continuously in the coating material, serving to stir and scrape the same thoroughly away from the bottom of the tub and to keep the material in proper condition for use. The scoop 27 performs also a similar function. At each forward stroke the scoop 27 carries a quantity of coating material, and on encountering the lower face of plate 28 (the plate and scoop being shaped so as to cooperate to produce the desired result) this material is squeezed or squirted out into trough 20. The coating roll 7 is provided with a bucketed, pervious or absorbent surface and this surface is also preferably compressible or elastic. In rotating the coating roll comes in contact with the coating material in the trough and carries this material up and into contact with the lower surface of the biscuit as they pass, applying to them an even coat of the material. Surplus coating material in trough 20 runs out at the ends and top of the trough back into the tub 21. It is preferred that the proportions of scoop 27 or its rate of motion be such that a considerable excess of coating material is delivered into the trough over what is immediately used. This insures a copious circulation of coating material and keeps the same in the best condition for use. The shape of the plate 28 and scoop 27 may be widely varied to meet different condi-

tions. By changing the shape of scoop 27 slightly and making its discharge point somewhat higher than that shown in the drawing the plate 28 may sometimes be 5 omitted and the coating material may spill from scoop 27 into trough 20.

The features of this invention, and especially the means of supplying coating material to the roll, I believe to be broadly new 10 with me, and I do not limit myself in any respect to details.

I contemplate any changes which may be made within the spirit and scope of the invention.

15 What I claim is:

1. In a machine for coating, a coating roll, feed and delivery mechanism, a receptacle for coating material, and a scoop moving below said mechanism for supplying coating 20 material to the roll.

2. In a machine for coating, a coating roll, a receptacle for coating material, a trough below the roll, and a scoop for carrying coating material from the receptacle and depositing it in the trough.

3. In a machine for coating, a coating roll, a receptacle for coating material, a scoop, means for moving said scoop into and out of the receptacle, and a plate coöperating with 30 the scoop to supply said coating material to the roll.

4. In a machine for coating, a coating roll, a trough below the roll, a receptacle for coating material, a scoop arranged to oscillate in 35 said receptacle, and a plate coöperating with the scoop to deposit coating material in the trough.

5. The combination of a coating roll, a tub, a frame mounted to oscillate in the tub, a trough beneath the coating roll, a scoop on 40 the frame, a plate coöperating with the

scoop to deposit coating material in the trough, and means for oscillating the frame.

6. The combination of a coating roll, a tub, a frame mounted to oscillate in the tub, a trough beneath the coating roll, a scoop on 45 the frame, an agitator blade on the frame, a plate coöperating with the scoop to deposit coating material in the trough, and means for oscillating the frame.

7. In a coating machine, the combination of a coating roll, a trough beneath the roll, a tub below the roll and trough for coating material, a pivotally mounted plate adjacent to the trough, and an oscillating scoop serving to raise the coating material from the tub and discharge it into the trough by contact with the plate.

8. In a coating machine, the combination of a coating roll, a trough, a tub for coating material having a cylindrical inner surface, a shaft, a scoop carried by the shaft serving to elevate coating material from the tub and discharge it into the trough, and an agitator carried by the shaft and moving in 60 close proximity to the surface of the tub.

9. In coating mechanism, the combination of a coating device, a container adapted to retain coating material adjacent to said device, a reservoir below the coating device, a conveyor for moving coating material from the reservoir to said container, and means for raising and lowering the reservoir to 70 clear it from said coating device and conveyor for placement and replacement.

In testimony whereof I have affixed my signature in the presence of two witnesses.

FREDERICK E. GOLDSMITH.
